CASTING APPARATUS.

1,308,862.

Specification of Letters Patent.

Patented July 8, 1919.

Application filed January 5, 1917. Serial No. 140,710.

To all whom it may concern:

Be it known that we, CHARLES PACK and LEO FRANK NOCK, both citizens of the United States, residing, respectively, at the borough 5 of Brooklyn, city of New York, county of Kings, and State of New York, have invented certain new and useful Improvements in Casting Apparatus, of which the following is a specification, reference being 10 had therein to the accompanying drawings, which form a part thereof.

Our invention relates to casting apparatus and more particularly to a type thereof having the mold cavities formed by a plastic 15 composition which apparatus is particularly adapted for use in the production of what is known as "finished" castings.

In the production of finished castings, it is essential not only to secure accuracy in 20 the dimensions of the casting produced, but to have the finish of the castings smooth and the dimensions thereof accurate, and uniform in all castings made. Such castings ordinarily, are made in large numbers 25 and when drawn from the pattern require little or no machine finishing excepting that incidental to the removal of the sprue and, sometimes, the drilling of holes. In the process of producing the mold for making 30 these castings we have been able to guard against the presence of fins at the parting between the mold parts, when bi-part molds are used; to provide for the production of a number of castings in a single mold; and 35 to control the chill of the casting so as not to interfere with the flow of the molten metal through the ingate of the mold. The apparatus of our present invention is designed to so control the molten metal as to 40 avoid all likelihood of dross, or other impurities, entering the mold cavities, thus avoiding the presence of either concealed or superficial defects in the castings.

We secure these results by providing the 45 molding apparatus, which term in this application includes as a part thereof the mold itself, having a supplemental ingate of such capacity that when the metal is poured thereinto, dross will accumulate in this ingate and only clean metal will flow to the gate cavity and the mold cavity. We have found in actual practice that the best result can be secured by forming a constriction 50 either in the main ingate to the mold, or in

the supplemental ingate, so as to retard the 55 flow of the metal momentarily and permit the stratification, or separation, of the clean metal and the dross, the constricted portion of the ingate forming an automatic skimmer which will accomplish this result. In order 60 to economize in the volume of plastic entering into the molding apparatus, the supplemental ingate is formed in a weighted member which also serves to hold the mold in close engagement with the base upon which 65 it rests and the parts together, while pouring. We have found it necessary to avoid a too rapid chilling of the metal in this supplemental ingate and to facilitate the drawing of the casting to provide a refractory lining therefor.

In this manner, the metal as it is poured into the mold, contacts only with a refractory substance, the low conductivity of which facilitates the flow of the metal and 75 results in a high percentage of perfect castings. Some molds, however, are provided with chills so as to control the setting or solidification of the metal of the casting after it enters the mold cavities.

The invention consists primarily in a molding apparatus embodying therein a mold formed of a plastic composition having an ingate and a supplemental weighted member having an ingate registering with the ingate 80 of the mold and adapted to be superimposed upon said mold, the ingate of said supplemental member being formed of refractory material and of a capacity sufficient to permit the accumulation of dross therein; and 85 in such other novel features and combination of parts as are hereinafter described and more particularly pointed out in the claims hereto appended.

Referring to the drawings:—

Figure 1 is a plan view of a mold embodying our invention;

Fig. 2 is a section on the line 2—2 of Fig. 1;

Fig. 3 is a similar view of a modified 100 form thereof; and

Fig. 4 is a plan view of one of the mold parts containing the gate cavity and its branches.

Like letters refer to like parts throughout 105 the several views.

In the accompanying drawings, we have shown the invention in connection with an

apparatus embodying therein a bi-part mold, although it is apparent that the number of parts of the mold is immaterial to the invention.

- 5 In the embodiment of the invention shown in the drawings, *a* indicates a mold part having therein a gate consisting of a run *b*, branches *c* leading to each mold cavity and an enlarged ingate *d*; and a mold member *e* having therein mold cavities *e'* and a cavity *e''* forming a chill opening for the casting. In pouring, the section *e* of the mold is supported upon a base *f* formed of a material having a chilling action, which is preferably 15 provided with a thin insulation *f'* composed of asbestos or other suitable material. This construction avoids any possibility of the metal bonding or freezing to the support *f* and also avoids a too rapid transfer of heat 20 units from the castings to the base, conduction of heat from the castings to the base *f* being desired, under a certain control. The mold part *a* rests upon the part *e* and surrounding said section *a* is a weighted member *g* having an enlarged portion *g'* through which passes an opening *g''* forming a supplemental ingate in register with the ingate *d*. This supplemental weighted member *g* serves to hold the mold firmly upon the base 30 *f* and when a plurality of parts are used in the mold, it also serves to hold these parts in close contact throughout the pouring operation. The ingate *g''* is of sufficiently great capacity to permit the rapid pouring of the 35 entire charge of metal with a relatively lower rate of flow of the metal through the ingate *d* and the run *b*. In the preferred form of the invention we provide either the main ingate *d* or the supplemental ingate *g''*
- 40 with a transverse partition, such as *h*, having a constricted passageway therethrough, so as to momentarily check the metal as it is being poured and thus facilitate the separation of the clean metal and the dross in the 45 supplemental ingate *g''*. This partition we have termed a "skimmer" and we preferably arrange it in the ingate *d* in order to secure the maximum capacity between the run *b* and the open mouth of the ingate *g''* and to 50 insure a more thorough separation of the clean metal and the dross by permitting a more rapid pouring and affording a longer interval within which the separation above referred to will take place.
- 55 To prevent the chilling of the metal poured into the ingate *g''* and minimize likelihood of its freezing thereto; and to facilitate the drawing of the completed casting, we provide the ingate *g''* with a lining of refractory material *g''*, preferably consisting of the same composition as that employed in making the mold portions *a* and *e*.

The venting of the mold results from the method of making same, and the nature of the composition from which it is made, no

provision being required in the apparatus to secure the desired free venting of the mold.

By providing an ample ingate, as shown and described, we not only insure the delivery of clean metals to the various mold cavities, but a sufficient mass of metal in the ingate to avoid possibility of the premature solidification of the metal therein.

After the casting operation, sufficient time is allowed to permit the desired solidification of the casting, and before the casting is drawn the member *g* is removed from the mold parts, the lining *g''* remaining in the ingate *g''* or sliding therefrom and remaining about the ingate sprue.

The mold is then broken up and the castings removed therefrom and such machining as is required to remove the sprues is done. In making the molds, however, the various branches *c* are so positioned in relation to the mass of metal in the mold as to permit the separation of the sprue at a point where it will not interfere with the smaller parts of the castings. Where a chill is formed upon the casting, it is also necessary to remove this chill unless the nature of the casting be such as to permit this chill to form a part thereof.

It is not our intention to limit the invention to the particular form of mold shown in the accompanying drawings, nor to the particular arrangement of the run *b* and branches *c*, since such will vary with different castings.

Having described the invention, what we claim as new and desire to have protected by Letters Patent is:—

1. A casting apparatus embodying therein a two part mold, the upper section of which is formed entirely of a plastic composition, said mold having an ingate, and a supplemental member having an ingate registering with the ingate of the mold adapted to be superimposed upon said mold, and to bear upon the same sufficiently to prevent separation of the mold members when the casting is poured, and a separable lining of refractory material for the ingate of said supplemental member, said ingate having a capacity sufficient to permit the accumulation of dross therein.

2. A casting apparatus embodying therein a heat conductive base, and a mold formed of plastic composition having a mold cavity, an upwardly opening ingate and a chill opening extending from said mold cavity through the bottom of said mold to said base, said base being adapted to support said mold and conduct heat from the chill opening therein.

3. A casting apparatus embodying therein a mold formed of plastic composition having an upwardly opening ingate and a chill opening through the bottom thereof, and a heat conductive base adapted to support said

mold and conduct heat from the chill opening therein, said base having a thin facing of refractory material to retard the chilling action upon the mold and prevent the bonding of the metal thereto.

In witness whereof we hereunto affix our signatures in the presence of two subscriv-

ing witnesses, this 28th day of December, 1916.
